C. F. PAULUS.

PERCUSSION CAP DETONATOR.

1,378,272.

Patented May 17, 1921.

BY
Fraenkel and Richards,
ATTORNEYS

UNITED STATES PATENT OFFICE.

CHARLES F. PAULUS, OF EAST ORANGE, NEW JERSEY.

PERCUSSION-CAP DETONATOR.

1,378,272.

Specification of Letters Patent.

Patented May 17, 1921.

Application filed January 21, 1920. Serial No. 353,008.

To all whom it may concern:

Be it known that I, CHARLES F. PAULUS, a citizen of the United States, residing at East Orange, in the county of Essex and State of New Jersey, have invented certain new and useful Improvements in Percussion-Cap Detonators; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in detonating toys; and, the present invention relates, more particularly, to an improved percussion or paper-cap holding and exploding means for that class of detonating toys known in the art as cap-exploding canes or bomb-darts.

The present invention has for one of its principal objects to provide a simple and perfectly harmless toy, in which the cap or detonator holding and exploding means is of a most simple construction, the parts thereof having been reduced to a minimum, and being easily and quickly secured in their operative positions upon the end of a stick or rod-like body of a cane or bomb-dart, for the explosion of percussion or paper caps for children of all ages.

The present invention has for its further object to provide a novel construction of detonating toy having a fixed anvil in the form of an exploding pin or nail and a cap-receiving or holding yoke or element movably connected with the stick or rod-like body of the cane or bomb-dart, said yoke with the cap placed thereon being adapted to be forcibly brought against the head of the exploding pin or nail to cause the percussion or paper cap to be exploded with a loud report.

A further object of this invention is to avoid the use of a spring-actuated detonator rod, or to avoid the use of a movable igniting rod and a cup-shaped cap-holder or yoke, as heretofore made, and all of which are more or less inefficient in use, but to provide an exploding means of the general character and construction hereinafter more fully set forth, which shall be very simple in its construction, and most positive and operative in its action, and in which the ob-

jectionable features heretofore existing in devices of this character are fully overcome, so as to provide an enjoyable and non-dangerous cap-exploding or detonating toy. 60

Other objects of the present invention not at this time more particularly enumerated will be clearly understood from the following detailed description of the present invention. 65

With the various objects of the present invention in view, the said invention consists, primarily, in the novel detonating toy hereinafter set forth; and, the invention consists, furthermore, in the novel arrangements and combinations of the various devices and parts, as well as in the details of the construction of the said parts, all of which will be more fully described in the following specification and then finally embodied in the clauses of the claim which are appended to and which form an essential part of the said specification. 75

The invention is clearly illustrated in the accompanying drawings, in which:— 80

Figures 1 and 2 are a front and side view, respectively, of portions of a detonating stick or cane provided with a percussion or paper-cap exploding attachment made according to and embodying the principles of 85 the present invention; and Fig. 3 is a vertical sectional representation of the lower portion of the stick or cane and the said exploding attachment, said section being taken on line 3—3 in said Fig. 1. 90

Fig. 4 is a horizontal section of the said device, taken on line 4—4 in said Fig. 1, looking in the direction of the arrow X; and Fig. 5 is a plan view of a blank from which the movable, cap-receiving or holding yoke 95 of the detonating or exploding device is bent into shape.

Figs. 6 and 7 are a front and side view, respectively, of the lower portion of a stick or cane, provided with a percussion or 100 paper-cap exploding attachment of a slightly modified construction, but still embodying the principal features of the present invention; Fig. 8 is a horizontal section of the same, said section being taken on line 105 8—8 in said Fig. 6, looking in the direction of the arrow Y in said figure; and Fig. 9 is a plan view of a blank from which the movable cap-receiving or holding yoke of the detonating or exploding device shown in 110 said Figs. 6, 7 and 8 is bent into shape.

Similar characters of reference are em-

ployed in all of the said above described views, to indicate corresponding parts.

Referring now to the several figures of the drawings, the reference-character 1 indicates one form of complete detonating toy, shown more especially in Figs. 1 and 2 in the form of a detonating stick or cane, the same comprising a suitably shaped body, as 2, which may be made of wood and is of any suitable length and any desired cross-section. Upon its upper end, the said stick or cane may be provided with a hand-piece or holding member 4 of any desired configuration, but the same may be dispensed with, if desired.

Suitably disposed against the lower end 3 of the said stick or cane is a flat plate or element, as 5, which is centrally perforated as at 6, for the reception of a pin or nail 7 provided upon its end with an enlargement or head 8, for securely fitting the said plate 5 against the end of said body 2, substantially in the manner illustrated in the several figures of the drawings. Extending from the marginal edge-portions of the said plate or element 5 are centrally disposed projections or fingers, as 9 and 10, and movably disposed upon said projections or fingers 9 and 10 are the openings or perforations 14 and 15 formed in the right-angled wings or members 12 and 13 with which the main body-portion 11 of the percussion or paper-cap receiving and holding yoke is provided, the various parts of the yoke being held in their assembled relation with the plate 5 and the said pin or nail 7 in the manner clearly illustrated in said Figs. 1, 2, 3 and 4, and coöperating with said fixed plate 5 and the fixed pin or nail 7 in the manner to be hereinafter more fully described.

In lieu of the form of movable cap-receiving and holding yoke, shown in said Figs. 1 to 5 inclusive, the said yoke may be formed from a blank 16, shown more particularly in Fig. 9 of the drawings, the said blank being provided in its opposite edge-portions with a series of cut out parts forming a pair of recesses 17 and 18, and 19 and 20, upon each edge of the blank, and the respective end-portions 21 and 22 of said blank 16 being provided with the respective guiding fingers or projections 21 and 22, and 23 and 24. The perforated plate or anvil to be used with this form of yoke, and which is secured upon the end of the stick or cane by means of the pin or nail, as will be seen from Figs. 6, 7 and 8, in this case comprises a main body 25, centrally perforated, as at 26, and formed upon its opposite edge-portions with the cut-away portions or recesses 27 and 28, to provide the said anvil or plate with the guiding members or projections 29 and 30, and 31 and 32 for the wing-portions 33 and 34 of the yoke-blank 16, substantially as illustrated in the accompanying drawings.

In said Figs. 6, 7 and 8, I have shown the manner of disposing the angularly bent portions or wings of this modified construction of yoke in connection with the said anvil or plate 25, whereby these various devices are held in their movably connected and operative relation, as will be clearly evident.

Having in the foregoing described the general construction of a detonating toy, in this case in the form of a cane, I will now briefly set forth the manner of operating the device when it is desired to explode a percussion or paper-cap.

By raising the cane, and holding it above the surface of the body with which the yoke-member is to be brought into forcible contact, the said yoke-member will assume the suspended relation with respect to the other parts, shown in Figs. 1, 2, 3, 6 and 7 of the drawings, thereby enabling the placing of a percussion or paper-cap in its resting position upon said yoke and in the space formed between the said yoke and the anvil and exposed enlargement or head of the nail or pin.

By suddenly dropping the cane or stick, so that the lower and exposed surface of the yoke is forcibly brought in contact with an object or surface foreign to the cane, the yoke-member with the percussion or paper-cap resting thereon, will be rapidly moved toward the exposed enlargement or head of the nail or pin, the sudden engagement of the parts thereby causing the percussion or paper-cap to be exploded with a loud detonation.

While in the accompanying drawings, the detonating means is shown, and, in the present specification, is described in connection with body forming a cane or stick, it will be clearly understood that the detonating means may be used with the bodies or sticks of bomb-darts, or the like.

Of course I am aware that some changes may be made in the general arrangements and combinations of the several devices and parts, as well as in the details of the construction of the said parts, without departing from the scope of the present invention as set forth in the foregoing specification, and as defined in the clauses of the claim which are appended thereto. Hence, I do not limit my present invention to the exact arrangements and combinations of the several devices and parts as described in the said specification, nor do I confine myself to the exact details of the construction of the said parts, as illustrated in the accompanying drawings.

I claim:

1. A percussion-cap detonator comprising a main body, an anvil-plate fixed upon an end of said body, said plate being provided with oppositely located marginal projections, and a cap-receiving yoke, provided with right-angled wings having openings into and

through which said projections extend for movably connecting said yoke with said anvil-plate.

2. A percussion-cap detonator comprising
5 a main body, a perforated anvil-plate, a
nail having an enlargement or head, said nail
being adapted to be inserted in the perfora-
tion of said anvil-plate for securing said
plate in a fixed position upon the end of said
10 main body, said plate being provided with
oppositely located marginal projections, and
a cap-receiving yoke, provided with right-

angled wings having openings into and
through which said projections extend for
movably connecting said yoke with said plate 15
to permit its movement toward the enlarge-
ment of said nail.

In testimony, that I claim the invention
set forth above I have hereunto set my hand
this 15th day of January, 1920.

CHARLES F. PAULUS.
